Primary Examiner — Melody N Brown(74) *Attorney, Agent, or Firm* — Wood Herron & Evans LLP(57) **CLAIM**

The ornamental design for a front end of a vehicle, as shown and described.

DESCRIPTION

FIG. 1 is a right, front perspective view of a front end of a vehicle showing our new design;

FIG. 2 is a left, front perspective view thereof;

FIG. 3 is a rear, left perspective view thereof;

FIG. 4 is a front elevational view thereof;

FIG. 5 is a left side elevational view thereof;

FIG. 6 is a right side elevational view thereof; and,

FIG. 7 is a top view thereof.

In the Figures the parts of the vehicle outside of the broken line are shown in de-emphasized and half-tone portions for environmental and illustrative purposes only. These portions form no part of the claimed design. Rather, the inventive front end of a vehicle resides within the broken line, and the broken line represents an unclaimed boundary thereof.
